COMBINED CABINET AND WORK TABLE FOR PACKAGING SURGICAL GLOVES

William J. Hannon, Jr., Dorchester, Mass., assignor to
The Macbick Company, Cambridge, Mass., a corpora-
tion of Massachusetts

Filed July 23, 1962, Ser. No. 71,018

Term of patent 14 years

(Cl. D16—2)

F I G. 1

F I G. 3

F I G. 2

FIG. 1 is a front-side view in perspective of a combined cabinet and work table for packaging surgical gloves embodying the design of the present invention;

FIG. 2 is a top plan view of the article of FIG. 1; and
FIG. 3 is a rear-side view in perspective of the article of FIG. 1.

I claim:

The ornamental design for a combined cabinet and work table for packaging surgical gloves, substantially as shown.
